M. J. Griswell.
ATTORNEY

UNITED STATES PATENT OFFICE.

CHARLES BLIEBERGER, OF NEW YORK, N. Y.

ACOUSTIC DIAPHRAGM.

Application filed September 4, 1926. Serial No. 133,723.

This invention relates to acoustic diaphragms such as are used in the reproduction and recording of sound.

In recording sound the diaphragm is set in motion by the waves of the sound which is to be recorded, and its motion is passed on to suitable recording mechanism. In reproducing sound the diaphragm is actuated by suitable means (usually mechanical or electrical) in accordance with the sound to be reproduced and the diaphragm sets up the necessary waves in the air to produce the desired sound. The action of the diaphragm in the two cases is analogous, as is well understood in the art; and for the sake of simplicity the following disclosure will refer primarily to the action of the diaphragm in reproducing sound. It is to be understood, however, that the diaphragm may be used either for reproduction or recording.

The conventional diaphragm responds more readily to certain frequencies than it does to others. Both music and speech consist of a wide range of frequencies and for faithful reproduction the diaphragm must vibrate at any given frequency with a volume corresponding to the volume of that frequency in the original sound. Otherwise, that frequency will be either accentuated or diminished in the reproduced sound, thus causing distortion. Various expedients have been resorted to in an attempt to cause a diaphragm to give a volume of vibration at any particular frequency which will correspond with the volume of that frequency naturally present in the sound being dealt with. However, the expedients have been only partly successful, with the result that the diaphragm has always caused an objectionable amount of distortion in the recording and reproduction of sounds.

The general object of the present invention is to provide an acoustic diaphragm which will respond to the various frequencies present in speech and music with a volume (as to the individual frequencies) which corresponds to the volume of the individual frequencies present naturally in speech and music. Stated in another form, this object is to provide a diaphragm which will operate without distortion in the recording or reproduction of speech and music.

The above and other objects of the invention are accomplished by means of a dia-

phragm having various zones adapted to respond to consecutive bands of frequencies extending from the very low to the very high frequencies present in speech and music. The invention is disclosed in the form of a diaphragm having zones which are wedge-shaped in cross section, thus making such diaphragm zones of varying thickness, whereby each zone will respond readily to all of the frequencies of a certain band of frequencies. This construction enables the diaphragm to vibrate with a volume at practically any frequency (in the voice or music range) which corresponds with the volume of that frequency present in the natural sound. A diaphragm having segments thereof of wedge-shape cross section will respond without appreciable distortion to music and speech and in accordance with the statutory requirements a circular form is being disclosed as the preferred form of the invention by way of illustration but not in the limiting sense.

Fig. 1 is a plan view of one form of diaphragm.

Fig. 2 is a cross section on line 2—2 of Fig. 1.

Fig. 3 is a plan view of another form of diaphragm.

Fig. 4 is a cross section on line 4—4 of Fig. 3.

Fig. 5 is a plan view of a diaphragm having diaphragm zones of proportions different from those shown in Fig. 3.

Fig. 6 is a cross section on line 6—6 of Fig. 5.

Referring to Figs. 1 and 2, the diaphragm designated as a whole by 10 has a lower plane surface 11 and an upper plane surface 12. These two surfaces are parallel to each other, as shown in Fig. 2, and each surface is a segment of a circle greater than a semi-circumference. The chordal boundaries of the two segments are illustrated as parallel to each other as shown in Fig. 1, so that between the overlapping portions of the segmental surfaces 11 and 12, there is formed a band like diaphragm zone 15 of uniform thickness. On the under side of the disk is a plane segmental surface 13 inclined to the surface 11 as shown in Fig. 2. Between this segmental surface 13 and the upper surface 12 there is formed a segment shaped diaphragm zone of wedge shaped cross-section

16. The base of the wedge is at the chordal boundary between segments 11 and 13 and the sharp edge of the wedge is at the periphery of the disk. Similarly, on the upper 5 side of the disk there is a plane segmental surface 14 inclined to the surface 12 to form a second segmental diaphragm zone of wedge-shaped cross section 17.

As shown in both Figs. 1 and 2, the wedge shaped segmental diaphragm zone 16 is larger than the wedge shaped segmental zone 17, and since the bases of both wedges are of the same thickness, the diaphragm zone 16 is more flexible than the zone 17. Accordingly, the zone 16 is adapted to respond in general to one band of frequencies while the zone 17 is adapted to respond in general to another band of frequencies, and the zone 15 to respond in general to still another 20 band of frequencies.

In Figs. 3 and 4, the diaphragm is designated as a whole by 18. The under surface 19 comprises a circular section of a single plane and the upper surface consists of two 25 inclined segmental plane surfaces 20 and 22, which meet at a chordal boundary 21. The diaphragm has its greatest thickness at the chordal boundary 21 so that there is formed two segmental wedge-shaped diaphragm zones 23 and 24 separated by the chordal boundary 21, which forms a ridge across the surface of the diaphragm. The diaphragm zone 23 is more flexible than the zone 24 with the result that the zone 23 is in general 35 adapted to respond to low frequencies and the zones 24 to respond in general to medium frequencies, while the highest frequencies are in general, handled by that portion of the diaphragm contiguous to the ridge 21.

40 The diaphragm shown in Figs. 5 and 6 and designated as a whole by 25 is similar to the diaphragm of Figs. 3 and 4. It consists of two segmental diaphragm zones 30 and 31 separated by a chordal ridge 27 and formed 45 between the lower plane surface 26 and two segmental plane surfaces 28 and 29. The diaphragm of Figs. 5 and 6 performs in much the same manner as the diaphragm of Figs. 3 and 4, but since the more flexible section 31 is larger in proportion than the more 50 flexible section 23, the diaphragm of Figs. 5 and 6 is adapted to handle sounds which predominate in low frequencies, e. g., certain notes in organ music.

55 I have found that diaphragms having wedge-shaped segmental zones will faithfully handle speech and music without appreciable distortion. In some types of music, low frequencies predominate while in others 60 medium or high frequencies predominate, and it may be desirable to vary the relative sizes of the diaphragm zones according to the type of music which is to be handled. An example of such variation is shown by 65 the diaphragms of Figs. 3 and 5.

The diaphragms may be made of any suitable material, preferably of uniform density, and of such sizes and shapes as are best adapted for telephone, radio, phonograph or other acoustical work.

70

For the sake of convenience in the foregoing disclosure, reference has been made to the "upper" and "lower" surfaces of the diaphragm referring only to the position of the surfaces as shown in the drawings. 75 Of course, it is obvious that the diaphragm may be used in any position and hence the references to "upper" and "lower" are only for convenience in designating the surfaces in the positions in which the diaphragms 80 are shown in the drawings.

It is realized that the invention may be embodied in forms other than those particularly disclosed and hence the foregoing disclosure is to be considered as illustrative 85 and not as limiting.

Having thus described my invention, what I claim is:

1. An acoustic diaphragm having two zones of wedge-shaped cross section extending 90 across the disk, and a zone of approximately uniform thickness and uniform width extending chordally across the disk between the wedge-shaped zones.

2. An acoustic diaphragm having on each 95 side a plane segment-shaped surface larger than a semicircle, the chordal boundaries of the segments being parallel and said plane surfaces being parallel; and two segment-shaped zones of wedge-shaped cross 100 section, said zones being bounded by said chordal boundaries and the peripheral edge of the disk.

3. An acoustic diaphragm comprising a plurality of zones of wedge-shaped cross-section, and with the thickest portion of said cross section extending from edge to edge 105 of the diaphragm.

4. An acoustic diaphragm comprising two segmental zones of wedge-shaped cross section, one zone being larger than the other.

5. An acoustic diaphragm comprising a plurality of wedge-shaped cross section portions of different sizes extending across the diaphragm.

6. A substantially disk-shaped acoustic diaphragm comprising two segmental zones of wedge-shaped cross section, and a zone of substantially uniform thickness separating said wedge-shaped zones.

7. An acoustic diaphragm comprising a diaphragm zone formed by two substantially plane surfaces on opposite faces of the diaphragm, the surfaces being opposite one another and at an angle to each other to give the zone a wedge-shaped cross section, and with the base of said wedge-shaped cross section extending across said diaphragm from edge to edge.

8. An acoustic diaphragm comprising a 130

plurality of diaphragm zones, each zone being formed by two substantially plane surfaces on opposite faces of the diaphragm, the surfaces being opposite one another and at an angle to each other to give the zones wedge-shaped cross sections, and with the greater portion of said zones being adjacent the thickest portion of the cross section.

9. An acoustic diaphragm comprising a plurality of diaphragm zones, the zones being of different sizes and each zone being formed by two substantially plane surfaces on opposite sides of the diaphragm, the surfaces being opposite one another and at

an angle to each other to give the zones wedge-shaped cross sections. 15

10. An acoustic diaphragm comprising two diaphragm zones, each zone being formed by two substantially plane surfaces on opposite sides of the diaphragm, the surfaces being opposite one another and at an angle to each other to give the zones wedge-shaped cross sections, and with the thickest portion of said cross section extending across the diaphragm from edge to edge. 20 25

This specification signed this 3rd day of September, A. D. 1926.

CHARLES BLIEBERGER.
